(57) CLAIM

The ornamental design for a handle for food roasting utensil, as shown and described.

DESCRIPTION

FIG. 1 is an isometric view of a handle for food roasting utensil showing my new design;

FIG. 2 is a front side view thereof;

FIG. 3 is a rear side view thereof;

FIG. 4 is a left side view thereof;

FIG. 5 is a right side view thereof;

FIG. 6 is a top side view thereof; and,

FIG. 7 is a bottom side view thereof.

The broken lines illustrate portions of the handle for food roasting utensil and form no part of the claimed design.
